UNITED STATES PATENT OFFICE.

SECUNDO L. CASELLA, OF ALMA, CALIFORNIA.

FRUIT-PACKING FORM.

SPECIFICATION forming part of Letters Patent No. 660,362, dated October 23, 1900.

Application filed August 23, 1900. Serial No. 27,818. (No model.)

To all whom it may concern:

Be it known that I, SECUNDO L. CASELLA, a citizen of the United States, residing at Alma, in the county of Santa Clara, State of California, have invented an Improvement in Fruit-Packing Forms; and I hereby declare the following to be a full, clear, and exact description of the same.

My invention relates to an apparatus which is designed for rapidly filling baskets or packages with fruit, such as grapes, berries, &c., which are ordinarily packed into small veneer baskets. The apparatus consists of a rectangular frame having elastic metallic plates fixed and projecting outwardly in one direction from the frame. These plates are approximately the shape of the basket which is to be filled, and between the plates is fitted a slideable block, which may be moved to the top or bottom of the plates, with means for holding it in either position. The frame is fulcrumed in a yoke, which yoke is fixed to the table or bench where the work is to be done, and the frame is turnable within the yoke, so that it can be reversed, with suitable locking devices for either position. The frame being turned so that the plates project upwardly, the block or plate within the space inclosed by the plates drops to the lower side and is there supported while the space between the plates is filled with the fruit. The basket is then placed over the plates and the device reversed in the frame. The basket can then be withdrawn, and the fruit is pressed into the basket by the movable plate or follower.

My invention also comprises details of construction which will be more fully explained by reference to the accompanying drawings, in which—

Figure 1 is a vertical section through the apparatus, showing it in the position to be filled. Fig. 2 is a similar view reversed and ready to be discharged. Fig. 3 is a plan view of Fig. 2.

A is the frame, which is here shown as rectangular, but may be made of any shape corresponding with that of the basket or package which is to be filled. The frame may also be made of any suitable or desired material, either wood or metal. To the inner side of this frame are fixed the elastic metal plates

2, projecting outwardly in one direction. These plates are separated at the angles, as here shown, and correspond closely in shape 55 with the form of the package to be filled. The frame A is journaled in a yoke or support 3, which yoke is secured to the table, bench, or other convenient support by means of clamps, (shown at 4,) so that the whole apparatus projects from one side of the table.

Upon one side of the frame A are made pin-holes or other equivalent locking devices, as at 5, and the spindle upon that side carries a plate or sleeve, with pins 6, which are 65 adapted to enter the pin-holes 5 when the frame lies in the horizontal position with either side up. By means of a spring, as at 7, the frame is normally moved, so that the pins will drop into the holes whenever they 70 are brought in line therewith. In order to turn the frame, it is only necessary to move it in line with its axis or support until the pins are disengaged from the holes. Then when it is reversed the action of the spring 75 will cause the pins to again drop into the holes and lock the frame in position.

Between the plates 2 is a follower-block 8, which is connected by pivot-links 9 with the inner side of the frame A, and this block may 80 have a handle, as at 10, upon one side. The movement of this follower, as allowed by the links 9, is sufficient to allow it to drop to the full depth of the space between the plates 2 in the direction of the bottom and similarly 85 to approximately the full depth in the opposite direction, where it is arrested by any suitable stops, as at 11.

The operation of the device will then be as follows: The frame A being turned in the 90 yoke 3 to occupy the position shown in Fig. 1, the plates 2 stand in the shape of an inverted basket, and the follower 8 will drop to the lower side or on a level with what would be the top of such basket. The fruit 95 to be packed is then placed between the plates 2 until the space between the plates is filled. The basket (which is outlined in dotted lines in Fig. 1 and shown in full lines at 13, Fig. 2) is then placed over the plates 2, extending down exterior to them and resting upon the surface of the frame A. The handle 12, connected with the pivot stem or axis of the plate, is then moved, so as to press the spring

7 and withdraw the pin 6 from the holes 5, which allows the frame to be reversed, the basket being held in position by hand or otherwise while this reversing takes place, and 5 upon releasing the handle 12 the pins will again engage the holes and hold the frame in this position, in which the basket is then right side up, as shown in Fig. 2, and it is then removed downwardly from the plates 2. The 10 follower 8 is at the same time pressed down between the plates as far as the links 10 will allow, and this presses the fruit out into the basket, which can then be removed and the frame A again reversed in position to be again 15 filled.

By this means the operator is enabled to rapidly and accurately fill baskets and prepare them for the market.

Having thus described my invention, what 20 I claim as new, and desire to secure by Letters Patent, is—

1. An apparatus or form for packing fruit, consisting of a centrally-pivoted reversible frame having elastic plates projecting from 25 one side, corresponding in shape with the form of the package to be filled, said plates

separated at the angles, a follower movable between said plates adapted to form a bottom while the space above is being filled and to discharge the fruit into the basket when the 30 frame has been reversed.

2. An apparatus or form for packing fruit, consisting of a frame, a yoke in which said frame is horizontally journaled and turnable, latching devices by which the frame is held 35 in horizontal position with either face uppermost, elastic plates projecting from one side of said frame, and having a form corresponding with that of the package to be filled, a follower, links by which said follower is suspended between said plates and movable from top to bottom thereof whereby the space between the plates may first be filled, a basket or package placed over the space, and the device reversed, and the fruit pressed into the 40 basket as the latter is removed from the form.

In witness whereof I have hereunto set my hand..

SECUNDO L. CASELLA.
